GEORGE HENRY SAND, OF CINCINNATI, OHIO

TYPE JUSTIFYING MECHANISM

Application filed July 19, 1930. Serial No. 489,027.

This invention relates to a title line equalizing device for equalizing the rows of set type in a book binder's printing pallet so that they may be brought into symmetry and thus enable the titles of books to be artistically printed.

One important object of the invention is to provide means for simultaneously adjusting a number of rows of loose set type in a book binder's pallet into symmetrical relation.

A second important object of the invention is to provide means for holding the rows of loose type in their symmetrical relation during the locking up of the form or pallet.

15 A third important object of the invention is to provide a stand on which a book binder's pallet may be centered for setting type therein, the stand carrying novel mechanism for centering lines of type laterally of the 20 pallet.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

30 Figure 1 is a side elevation of the invention with a pallet in position thereon.

Figure 2 is a plan view thereof.

Figure 3 is an enlarged plan view of the top of the stand with the pallet removed.

35 Figure 4 is a section on the line 4—4 of Figure 3.

Figure 5 is a section on the line 5—5 of Figure 4.

40 Figure 6 is an enlarged plan view of a pallet suitable for use herewith.

Figure 7 is a section on the line 7—7 of Figure 6.

Figure 8 is a section on the line 8—8 of Figure 6.

45 Figure 9 is a plan view of a plunger used with the pallet.

Figure 10 is a side elevation of the plunger.

Figure 11 is a face view of said plunger.

50 Figure 12 is a view similar to Figure 6

showing the type loosely arranged in the pallet before equalizing.

In the embodiment of the invention here shown there is provided a stand having legs 10 and an inclined top 11 whereon rests a 55 suitable head frame. This head frame includes a pair of end plates 12 tied together by a bottom or base 13. Extending between the lower parts of the plates 12 adjacent the sides thereof is a pair of pivot bolts 14 having the angle portions of certain bell crank levers pivoted thereon for independent rocking movement. Each lever has a substantially vertical arm 15 and a substantially horizontal arm 16. These levers are arranged in cooperating pairs with the horizontal arms 16 of each pair projecting toward each other and interlocked as at 17. Between the bell cranks are arranged spacer bars 18 which have their ends supported on the bolts 14. 60 A pull rod 19 is secured to the horizontal arm of one lever of each pair through an opening 20 in the base 13. A treadle lever 21 has one end pivoted to a bracket 22 fixed on the lower part of one pair of legs 10 and projects forwardly to terminate in a treadle 23. The rods 19 pass downwardly through suitable openings in this lever and extend for some distance therebelow to terminate each in a head 24. Surrounding each rod between the lever 21 and head 24 is a coiled compression spring 25. By this means downward tension may be exerted on the several rods while permitting unequal downward movements.

Obviously, as shown in Figure 4, downward movement of a rod will draw the arms 15 of the pair of bell cranks controlled thereby equally inward at their free upper ends. Undercut strips 26 connect the upper edges of the ends 12 and a U-shaped spring frame 27 80 has its legs connected to the ends 12 and projects laterally therefrom so that springs 28 may each have one end secured to this frame and its other end secured to a respective vertical leg 15 of a bell crank, these springs urging the legs 15 of each pair of bell cranks apart.

The pallet used in connection with the parts just described consists of a base 29 having a dove-tail tongue 30 extending from end 100

to end of its under side. This tongue is of proper dimension to fit between the strips 26 and a stop pin 31 is provided on the head to limit movement of the pallet and ensure its being properly positioned. Extending up from the side portions of the base 29 are side pieces 32 provided with suitable slots 33 for the reception of plungers 34 arranged in opposed pairs corresponding in position to the 10 positions of the pairs of bell cranks and each bell crank arm 15 is provided with a notch 35 to receive the end of a respective plunger. Spacer plates 36 are interposed between the pairs of plungers and at one end of the base 15 29 is a stop rib 37 while the other end is provided with a threaded boss 38 wherethrough passes a clamp screw 39 provided with a handle 40. Type T are loosely set up in the spaces between the proximal ends of the pairs of 20 plungers. The pallet is then positioned on the head so that the outer ends of the plungers are engaged in the notches 35 after which the pedal is depressed. This will effect inward movement of the plungers of each pair 25 symmetrically with respect to the longitudinally extending center line of the pallet so that the type T in the various rows will be symmetrically positioned in the pallet. The handle 40 is then rotated so that the type are 30 tightly gripped between the spacers 36 after which the treadle is released and the pallet may be removed.

There has thus been provided a simple and efficient device of the kind described and for 35 the purpose specified.

It is obvious that minor changes may be made in the form and construction of the device without departing from the principles involved. It is therefore desired to include, 40 as the invention, all forms which properly come within the scope claimed.

Having thus described the invention what is claimed is:—

1. A type justifying mechanism for title 45 printing including a pallet having means for supporting lines of type, pairs of plungers, the plungers of each pair being arranged at opposite ends of a respective line of type, a head supporting said pallet, bell cranks supported on said head and arranged in pairs, one arm of each bell crank engaging a respective plunger, the remaining arms of each 50 pair being interlocked, pull mechanism for moving the pairs of bell cranks simultaneously, and means bearing against the upper and lower sides of the lines of type to clamp the 55 type against movement upon said type being centered in the pallet.

2. A type justifying mechanism for title 60 printing including a pallet having means for holding lines of type, means for simultaneously moving the type to cause the lines to assume symmetrical positions in relation to a pallet center line, and means bearing 65 against the upper and lower sides of the lines

of type to clamp the type against movement upon said type being centered in the pallet.

3. A type justifying mechanism for title 70 printing including a pallet having means for supporting lines of type, pairs of plungers, the plungers of each pair being arranged at opposite ends of a respective line of type, means for moving the plungers of each pair symmetrically inward, and means bearing against the upper and lower sides of the 75 lines of type to clamp the type against movement upon said type being centered in the pallet.

4. A type justifying mechanism for title 80 printing including a pallet having means for supporting lines of type, pairs of plungers, the plungers of each pair being arranged at opposite ends of a respective line of type, a head supporting said pallet, bell cranks supported on said head and arranged in pairs, 85 one arm of each bell crank engaging a respective plunger, means to move the bell cranks of each pair simultaneously and symmetrically, and means bearing against the upper and lower sides of the lines of type to clamp 90 the type against movement upon said type being centered in the pallet.

5. A type justifying mechanism for title 95 printing including a pallet having means for supporting lines of type, pairs of plungers, the plungers of each pair being arranged at opposite ends of a respective line of type, a head supporting said pallet, bell cranks supported on said head and arranged in pairs, 100 one arm of each bell crank engaging a respective plunger, the remaining arms of each pair being interlocked, pull mechanism for moving the pairs of bell cranks simultaneously, and means bearing against the upper and lower sides of the lines of type to clamp the 105 type against movement upon said type being centered in the pallet.

6. A type justifying mechanism for title 110 printing including a pallet having means for supporting lines of type, pairs of plungers, the plungers of each pair being arranged at opposite ends of a respective line of type, a head supporting said pallet, bell cranks supported on said head and arranged in pairs, one arm of each bell crank engaging a 115 respective plunger, the remaining arms of each pair being interlocked, pull mechanism for moving the pairs of bell cranks simultaneously, said pull mechanism including yieldable springs whereby to permit one pair of the plungers to operate upon stoppage of movement of another pair of plungers, and means to clamp the type against movement upon said type being centered in the pallet.

Signed at Cincinnati, Ohio, this 25th day 120 of June, 1930.

GEORGE HENRY SAND.
